UNITED STATES PATENT OFFICE.

JOHN DEMAREST, OF NEW YORK, N. Y., ASSIGNOR TO THE J. L. MOTT IRON WORKS, OF SAME PLACE.

CISTERNS FOR WATER-CLOSETS.

SPECIFICATION forming part of Letters Patent No. 282,901, dated February 5, 1884.

Application filed July 21, 1883. (No model.)

To all whom it may concern:

Be it known that I, JOHN DEMAREST, of the city and State of New York, have invented an Improvement in Cisterns for Water-Closets, of 5 which the following is a specification.

Where cisterns are used with water-closets, it often happens that the necessary amount of water is not supplied to the basin to wash 10 thoroughly, in consequence of the pull being lifted and dropped suddenly. Frequently the pull is kept partly raised, in order that a continuous supply of water may run through the cistern into the water-closet.

The object of my invention is to insure sufficient water passing to the water-closet to thoroughly wash out the basin under all circumstances of use, and also to prevent the water running into the cistern when the pull is raised and held and the valve of the discharge-pipe is 20 off its seat, thereby preventing waste of water.

In the drawings, Figure 1 is a vertical longitudinal section of the cistern and valve. Fig. 2 is a plan of the same, and Fig. 3 is a section at the line $x-x$, Fig. 1.

25 $a-a$ are the sides, $b-b$ the ends, and c the bottom, of the cistern, all preferably in one piece of cast-iron. There is an opening in the bottom of the cistern for the pipe d , to which the pipe leading to the water-closet is coupled, and 30 said pipe d is secured to the cistern by the nut 2.

e is a valve-seat at the upper end of d .

The parts thus far described are of usual character.

35 f is a float at one end of the rod g , and the other end of said rod is pivoted at 3. This rod acts by the movement of the float to open or close the valve p in the delivery-pipe q and admit or shut off the supply of water to the cistern.

40 h is the lever that is operated by the wire or chain i , connected with the water-closet pull, and said lever is pivoted at 6 in bearing upon the top of the cistern. There is a slotted arm, t , suspended from the lever h by the pin or 45 screw s , and the rod g of the float passes through this slotted arm, for a purpose hereinafter explained.

The valve k is made with a slotted tubular portion, 15, within the pipe d , forming a guide for the valve, and at n there is a ring of india-rubber in a groove at the lower part of the tube

55 l . Around this tube l there is a tube, m , supported by the arms $8-8$ from l , and the bottom of the tube m is open, but the top is either made in one with said tube, or else closed airtight by a screw-cap, as shown. There is sufficient space between the tubes l and m to allow the water in the cistern to rise freely in said space to the same height as in the cistern.

60 I have shown a rod, v , screwed into the cup 60 of the tube m , and passing through a slot in the lever, and provided with button end v' , for said lever to act against in raising the valve k . When the water-closet pull is raised, the lever h raises the valve k from its seat and the water 65 rushes through the slotted portion of the valve to the pipe d and water-closet, and if the pull is kept raised sufficiently long all the water in the cistern passes to the water-closet basin. While the pull has been kept raised the float 70 has not descended as the water fell in the cistern, because the arm t held up the rod g of the float; hence the valve p was kept closed while the cistern was discharging; but so soon as the 75 closet-pull is released the lever h falls and allows the valve k to drop to its seat, and at the same time the rod g and its float fall, opening the valve p after k has closed, and allowing the water to run in and fill the cistern, when the valve p is again closed by the rising of the float. 80 If the pull is raised and dropped suddenly, the water at first rushes through the valve-seat; but as soon as the valve k closes upon its seat then the vacuum produced in the tube l causes the water in the space between the tubes l and 85 m to rise and flow over into the tube l , and away by the pipe d , and this siphon action continues until the water in the cistern has descended to the level of the mouth of the tube m . By this means nearly the same amount of water passes 90 to the water-closet basin, no matter whether the pull is raised suddenly and dropped, or whether the pull is kept raised, and by connecting the float-rod with the lever h by the slotted arm the lever h cannot be held in such a position that there will be a continuous discharge of water from the delivery-pipe through 95 the cistern into the water-closet, because the arm t holds up the float-rod whenever the closet-pull is raised and the lever h operated, and 100 said rod is kept raised so long as the valve k is off its seat, thereby keeping the valve p

closed. When the closet-pull is released, the valve *k* first closes upon its seat, and the further descent of the lever *h*, arm *t*, and float and rod *g* permits the latter to open the valve *p* and allows the water to run into the cistern. The length of the slot in *t* is such that the float is allowed to rise when the water runs into the cistern, and when the water has reached a determined level the rod lifts the valve and shuts off the supply of water to the cistern. The tube or pipe *l* of the valve is also the overflow pipe for cistern.

The valve *k* and tubes *l m* may be guided in any well-known manner.

15 I claim as my invention--

1. The combination, in a valve for water-closet cisterns, of the tube *l*, a ring, of rubber or other elastic material, at the lower end of said tube, and the tube *m*, supported by and surrounding the tube *l*, and made with an open lower end and closed top, substantially as and for the purposes specified.

2. The combination, in a valve for water-closet cisterns, of the tube *l*, a ring, of rubber or other elastic material, at the lower end of 25 said tube, the tube *m*, supported by and surrounding the tube *l*, and having an open lower end and closed top, and the slotted tubular guide below the lower end of tube *l*, substantially as and for the purposes set forth.

3. In a water-closet cistern, the valve *k*, open tube *l*, tube *m*, closed at the top, and valve-seat *e*, in combination with the lever *h*, slotted arm *t*, float *f*, and rod *g*, the latter within the slot of the arm *t*, and the valve *p*, operated by 35 said float, substantially as and for the purposes set forth.

Signed by me this 16th day of July, A. D. 1883.

JOHN DEMAREST.
